UNITED STATES PATENT OFFICE.

ARCHIBALD M. GREEN, OF CHELSEA, MASSACHUSETTS, ASSIGNOR OF ONE-HALF TO FRANK A. MARSTON, OF WINTHROP, MASSACHUSETTS.

HOISTING APPARATUS.

SPECIFICATION forming part of Letters Patent No. 779,275, dated January 3, 1905.

Application filed July 29, 1904. Serial No. 218,677.

To all whom it may concern:

Be it known that I, ARCHIBALD M. GREEN, of Chelsea, in the county of Suffolk and State of Massachusetts, have invented certain new and useful Improvements in Hoisting Apparatus, of which the following is a specification.

This invention relates to hoisting apparatus, and is especially intended for application to hoisting-buckets, or "coal-diggers," as they are sometimes termed, of the divided or clam-shell variety for loading or unloading coal to and from vessels.

As usually constructed heretofore the opening and closing chain or rope by which the bucket is opened and closed runs through a guide-opening formed in the head which is sometimes provided with a detachable wear-plate or fair-lead formed with an eye to take the wear from the eye in the head.

In none of the forms of construction heretofore employed, so far as I am aware, has there been used any form of antifriction device to lessen the wear on the rope or chain where it passes through the guide. The detachable plate does not reduce the wear on the rope. It merely takes the wear from the head or relieves the wear on the head and is cheaper to replace than to put in an entire new head; but it does not relieve the wear on the rope itself. The effect is to rapidly wear out the rope or wire, entailing great expense for frequent renewal. A chain is more likely to snap than is a wire rope, and it is more kinky and not so desirable for use.

The main object of the present invention is to provide an antifriction device or fair-lead for the rope which shall reduce the friction to a minimum, and thereby render it capable of use for a long time. There are other features of the invention relating to the guides.

The invention will now be fully described, reference being made to the accompanying drawings, and the novel features thereof will be particularly pointed out in the claims at the close of the specification.

In the drawings, Figure 1 is a plan of a hoisting-bucket embodying the invention. Fig. 2 is a side elevation. Fig. 3 is a front elevation. Fig. 4 is an enlarged detail plan

view of the fair-lead. Fig. 5 is a side elevation of Fig. 4. Fig. 6 is an enlarged detail plan of one of the guide-plates which are secured to the upper side of the weight along the edges of the slot in which the lower sheaves are pivoted. Fig. 7 is a side view of Fig. 6. Fig. 8 is an enlarged detail front elevation of the head-and sheaves for the opening and closing rope and showing the guards between the ears of the head and the sheaves and also between the sheaves themselves. Fig. 9 is a detail plan of a portion of the weight, showing the slot and sheaves and guide-plates. Fig. 10 is a detail side elevation of one of the sheaves and guards. Fig. 11 is a plan of Fig. 10. Fig. 12 is a section through the head on line 12-12 of Fig. 8.

The two shells 1 2, which form the bucket, are connected with the head 3 by the links 4, which are pivotally connected at the ends both with the bucket and the head, as well known. The two shells 1 2 are connected together by the pivot-shaft 5. The holding-rope 6 is connected with the head also in well-known manner.

The opening and closing rope 7 passes around the sheaves 8, which are mounted on the shaft 9 in the head, and around the sheaves 10, which are mounted on the shaft 5 in the slot in the weight 12, and up through the fair-lead, which is designated as a whole by the numeral 13.

The outer shell or casing 13 of the fair-lead is formed with a lower portion 13² of less exterior diameter than the upper portion and preferably tapering and is inserted as a sort of bushing in the guide 14, which is a part of the head 3. The shell is formed with a shoulder 15, which rests on the upper end of the guide 14.

Inside of the casing are three double-grooved rolls 16 16 16, together forming a triangle. A tubular shell 17, inside of the casing 13, is formed with three recesses in whose sides the said rolls 16 are journaled. The rolls are placed in a triangular position as nearly together as possible without interfering with each other, each groove in the rolls forming together with the adjacent groove in the adjacent roll, substantially a semicircle, thus

forming a central passage with three semicircular recesses. The wire or rope 7 passes through this central passage, and as it sways from side to side it swings into one or the other of these three recesses and rubs against the two grooves of the adjacent rolls forming the recess. The size of the grooves should be proportioned to the size of the opening and closing rope 7, so that the recess formed by two adjacent rolls will be of right size to receive the rope without being too large. The rope, therefore, whichever way it swings will engage a semicircular surface formed by a combination of two rolls which will furnish an antifriction roller-bearing for the rope.

In order to guide the wire or rope 7 as it passes around the lower sheaves 10, I provide guide-plates 18, 18, one on each side of the slot in the weight in which the sheaves are journaled. These guide-plates are formed with notches 19, one for each sheave, and are secured to the upper side of the walls of the slot.

Sometimes the opening and closing rope 7 has a tendency to jump off of the sheaves 8 or 25 to jump from one to the other and cause interference. In order to prevent this, I place guards 20 at the outer ends of the sheaves between the sheaves and the depending ears of the head 3 and also between the sheaves. In order to do this, I cut away the rim or form a hub 21 on each side of the sheaves to form shoulders on which the arc-shaped guards 20 will rest. The guard is formed with two fingers 22, 22, which extend upwardly and 35 brace the head 3 between them, so that as the sheaves revolve the guards are held from turning with the sheave.

As illustrated, the two hubs 21, which are adjacent to each other, form together a shoulder of double the width of the shoulder on the outer ends, and therefore the middle guard 20 will be of double the thickness of the outer guards, although, if preferred, the hubs could be made shorter on the inner side than on the outer, so that the two adjacent hubs taken together would be equal to one of the outer.

The holes 24 in the outer casing 13' of the fair-lead are for convenience of inserting in position the shafts 23, on which the grooved rolls 16 are mounted.

What I claim is—

1. A hoisting-bucket having a fair-lead provided with a plurality of double-grooved rolls pivoted with such relation to each other as to form a central passage with a plurality of arc-shaped bearings for the rope, each groove of each roll co-operating with the adjacent groove of the adjacent roll so that the two will form together an antifriction-bearing.

60. 2. A fair-lead for a rope having a plurality of double-grooved rolls pivoted with such angular relation to each other as to form a central passage with a plurality of arc-shaped recesses, each groove of each roll co-operating 65 with the adjacent groove of the next adjacent

roll so that the said two adjacent grooves will together form a roller-bearing for the rope.

3. A fair-lead for a rope having three double-grooved rolls pivoted in a triangular position forming a central passage, each groove forming together with the adjacent groove of the contiguous roll a semicircular recess and thus forming three semicircular roller-bearings each of which includes two of the rolls.

4. A fair-lead for a rope having a tubular shell, three double-grooved rolls, bearings within said shell in which said rolls are pivoted in a triangular position forming a central passage between them, each groove of each roll forming together with the adjacent groove of the next adjacent roll a semicircular recess and thus forming three semicircular roller-bearings each of which includes two of the rolls.

5. A hoisting-bucket having two shells pivoted together, a head, pivotal connections between the shells and head, an opening and closing rope, sheaves for said rope carried by said shells and by said head, and a fair-lead for said rope carried by the head, said fair-lead comprising an eye, a plurality of double-grooved rolls, bearings within said eye in which said rolls are pivoted in angular relation to each other forming a central passage between them, the grooves at the end of each roll forming together with the adjacent grooves of the adjacent rolls a series of arc-shaped recesses and thus forming a series of arc-shaped roller-bearings.

6. A hoisting-bucket having two shells pivoted together, a slotted weight carried by the pivot-shaft, a plurality of sheaves pivoted in the slot in said weight, an opening and closing rope which passes around said sheaves, and notched guide-plates secured to opposite sides of said slot having notches which receive the sheaves.

7. A hoisting-bucket having two shells pivoted together, a head, pivotal connections between the shells and head, an opening and closing rope, sheaves for said rope carried by said shells and sheaves carried by said head, the sheaves for the head being formed with projecting hubs, and guards having arc-shaped lower sides which rest on the hubs and upwardly-extending projections on the upper sides which engage the head and prevent rotation of the said guards with the sheaves.

8. A hoisting-bucket having two shells pivoted together, a head, pivotal connections between the shells and head, a slotted weight carried by the pivot-shaft of said shells, an opening and closing rope, sheaves for said rope pivoted in the slot in said weight, guide-plates secured to opposite sides of said slot having notches to receive the sheaves, sheaves carried by said head, formed with projecting hubs, guards having arc-shaped lower sides which rest on the hubs and upwardly-extending projections on the upper sides which en-

gage the head and prevent rotation of said guards with the sheaves, and a fair-lead on the head for the opening and closing rope, said fair-lead having a plurality of double-grooved rolls pivoted with angular relation to each other and forming a central passage with a plurality of arc-shaped recesses, each groove of each roll coöoperating with the next adjacent groove of the adjacent roll so that the

said two adjacent grooves form together a 10 roller-bearing for the rope.

In testimony whereof I affix my signature in presence of two witnesses.

ARCHIBALD M. GREEN.
